NITROAZOLINE COMPOUNDS AND
PROCESS THEREFOR

Herbert L. Wehrmeister, Terre Haute, Ind., assignor to
Commercial Solvents Corporation, New York, N.Y., a
corporation of Maryland
No Drawing. Filed Sept. 20, 1965, Ser. No. 488,776
23 Claims. (Cl. 260—307)

This invention generally relates to new nitroazoline compounds. In a first aspect, it relates to new nitrooxazoline and nitroimidazoline compositions and process for the production thereof. In a second aspect it relates to 2-(nitroalkyl)-2-azolines including aryl-, alkyl-, and alkenyl- substituted nitroalkyl azolines. In a more particular aspect it relates to the nitroazoline compounds

2-(3-nitro-3-alkyl)-2-oxazolines,
2-(1-alkyl-3-nitroalkyl)-2-oxazolines,
2-(1-arylalkyl-3-nitroalkyl)-2-oxazolines,
2-(1-alkenyl-3-nitroalkyl)-2-oxazolines,
2-(1-aryl-3-nitroalkyl)-2-oxazolines,
2-(3-nitro-3-alkyl)-2-imidazolines,
2-(1-alkyl-3-nitroalkyl)-2-imidazolines,
2-(1-arylalkyl-3-nitroalkyl)-2-imidazolines,
2-(1-alkenyl-3-nitroalkyl)-2-imidazolines,
2-(1-aryl-3-nitroalkyl)-2-imidazolines,

and a process for the production thereof.

2-oxazolines and 2-imidazolines have the following general formula:

where X is either the oxygen of the oxazoline ring, or it is the imide nitrogen of the imidazoline ring. It is conventional nomenclature to assign to X the position 1 and to number the remaining constituents of the ring in numerical sequence in a direction which will give the N the lowest number, i.e. in a counter-clockwise direction in the above formula. Thus the carbon atom between X and N is position 2, N is 3, etc. A carbon atom attached to the carbon atom in the 2-position is referred to in this specification as the alpha carbon atom.

There are numerous references in the art to the preparation of substituted oxazolines and imidazolines and compounds having substitution on each position of the ring are known. Several methods of preparing oxazolines and imidazolines are known but the most common method is to react an organic monocarboxylic acid with a 1,2-alkanolamine followed by dehydration to produce an oxazoline, or to react the organic acid with a 1,2-diamine followed by dehydration to produce the imidazoline. The carboxylic acid residue forms the substituent in the 2-position, and other substituents, if any, have usually been provided by the structures of the alkanolamines and diamines respectively.

There has been no disclosure in the prior art of either oxazolines or imidazolines of a method of substituting a nitroalkyl group on the alpha carbon atom after the ring has been formed. Neither has there been a disclosure of a nitroaliphatic radical attached to the alpha carbon atom in the 2-position.

It is an object of this invention to provide new nitroazoline compounds and a method for the preparation thereof.

A second object of this invention is to provide 2-(3-nitro-3-alkyl)-2-oxazolines.

2

A third object of this invention is to provide 2-(1-alkyl-3-nitroalkyl)-2-oxazolines.

A fourth object of this invention is to provide 2-(1-arylalkyl-3-nitroalkyl)-2-oxazolines.

A fifth object of this invention is to provide 2-(1-alkenyl-3-nitroalkyl)-2-oxazolines.

A sixth object of this invention is to provide 2-(1-aryl-3-nitroalkyl)-2-oxazolines.

A seventh object of this invention is to provide 2-(3-nitro-3-alkyl)-2-imidazolines.

Another object of this invention is to provide 2-(1-alkyl-3-nitroalkyl)-2-imidazolines.

A further object of this invention is to provide 2-(1-arylalkyl-3-nitroalkyl)-2-imidazolines.

A still further object of this invention is to provide 2-(1-alkenyl-3-nitroalkyl)-2-imidazolines.

Still yet another object of this invention is to provide 2-(1-aryl-3-nitroalkyl)-2-imidazolines.

Other objects of this invention will be readily apparent to those skilled in the art.

The azoline compounds

2-(3-nitro-3-alkyl)-2-oxazolines,
2-(1-alkyl-3-nitroalkyl)-2-oxazolines,

2-(1-arylalkyl-3-nitroalkyl)-2-oxazolines,
2-(1-alkenyl-3-nitroalkyl)-2-oxazolines,
2-(1-aryl-3-nitroalkyl)-2-oxazolines,

2-(3-nitro-3-alkyl)-2-imidazolines,
2-(1-alkyl-3-nitroalkyl)-2-imidazolines,

2-(1-arylalkyl-3-nitroalkyl)-2-imidazolines,
2-(1-alkenyl-3-nitroalkyl)-2-imidazolines,
2-(1-aryl-3-nitroalkyl)-2-imidazolines

are embraced by this invention. These oxazolines and imidazolines are represented by the following general structural formula:

where X can be —O— or

where Y can be an alkyl radical, aryl radical, arylalkyl, or hydroxyalkyl radical; R1 is hydrogen, alkyl, alkenyl, aryl or arylalkyl radical of from 1 to about 20 carbon atoms; R2 and R3 can be hydrogen, alkyl radicals having from 1 to 3 carbon atoms, hydroxymethyl or the group acyloxy methyl, with the proviso that when X is

R2 and R3 can be hydrogen or alkyl radicals of from 1 to 3 carbon atoms. R2 and R3 can be the same or they can be different.

When X is —O—, the following oxazoline is obtained:

When R_1 is hydrogen, the following oxazoline is obtained:

When X is

the following imidazoline is obtained:

and when R_1 is hydrogen, the following imidazoline is obtained:

The new compositions of this invention can be prepared by reacting about 1 mole of a secondary nitroalkane in the presence of a condensation catalyst with about 1 mole of a 2-ethenyl azoline having the general formula:

where X , R_1 , R_2 and R_3 have been previously defined. When X is $-\text{O}-$ and R_1 is hydrogen, the compound prepared is a 2-(3-nitro-3-alkyl)-2-oxazoline. When X is $-\text{O}-$ and R_1 is alkyl, the compound prepared is a 2-(1-alkyl-3-nitroalkyl)-2-oxazoline. When X is $-\text{O}-$ and R_1 is arylalkyl the compound prepared is a 2-(1-arylalkyl-3-nitroalkyl)-2-oxazoline. When X is $-\text{O}-$ and R_1 is alkenyl, the compound prepared is a 2-(1-alkenyl-3-nitroalkyl)-2-oxazoline. When X is $-\text{O}-$ and R_1 is aryl, the compound prepared is a 2-(1-aryl-3-nitroalkyl)-2-oxazoline. When X is

and R_1 is hydrogen, the compound prepared is a 2-(3-nitro-3-alkyl)-2-imidazoline. When X is

and R_1 is alkyl, the compound prepared is a 2-(1-alkyl-3-nitroalkyl)-2-imidazoline. When X is

and R_1 is arylalkyl, the compound prepared is a 2-(1-arylalkyl-3-nitroalkyl)-2-imidazoline. When X is

and R_1 is alkenyl, the compound prepared is a 2-(1-alkenyl-3-nitroalkyl)-2-imidazoline. When X is

and R_1 is aryl, the compound prepared is a 2-(1-aryl-3-nitroalkyl)-2-imidazoline.

In general the reaction is conducted by charging the reactants and catalyst into a suitable reaction vessel equipped with a reflux condenser and an agitator. A solvent can be used if desired and generally a solvent is preferred. The amount of catalyst used is preferably from about 0.5% to about 5% by weight based on the weight of the azoline, i.e. the oxazoline or imidazoline. Heat is applied from a heat source and the mixture is reacted at reflux temperature until the nitroalkane is consumed.

When nitroalkane is no longer condensing at the top of the reflux column, and the pot temperature has risen to at least 150° C., the reaction is substantially complete. The entire product of the reaction can be used if desired, but usually it is preferred to purify it. Any known method of purification, such as extraction or distillation can be used.

Distillation is a preferred method for compounds having sufficient thermal stability. To produce a distilled crude, the reaction product is distilled at a reduced pressure of from about 10 to about 15 mm., and the heads and tails are discarded. If still further refinement is preferred, the distilled crude is fractionated at a pressure of from about 1 to about 5 mm. The temperature at which these distillations occur will usually be less than 200° C. and will vary according to the ethenyl azoline used as the starting material as well as the pressure at which the distillation is conducted. In general, if R_1 is a long chain radical, the temperature tends to be higher than if R_1 is a short chain radical.

The preparation of a compound by this reaction is described in Example 3.

In another embodiment of this invention the ethenyl azoline is prepared in situ and is then reacted with the nitroalkane to form the nitro derivative. One method is to react about 1 mole of a 2-substituted azoline, e.g. a 2-alkyl azoline, a 2-alkenyl azoline, or a 2-arylalkyl azoline with about 1 mole of a 1-hydroxy-2-alkyl-2-nitroalkane, e.g. 2-nitro-2-methyl-1-propanol, preferably in the presence of a condensation catalyst. This reaction releases about 1 mole of water, which must be removed from the reaction mixture before the reaction is complete. The reaction is conveniently conducted in the presence of a water-entraining solvent at reflux temperatures and at ambient pressures. The heating is continued until water of reaction is no longer being released as can be determined by use of a water separator at the top of the reflux column.

The water-entraining solvent, such as hexane, octane, benzene, toluene, xylene, 2-nitropropane, etc., reduces the viscosity of the reaction mixture and removes azeotropically the water of reaction. After removal of water and water-entraining solvent by distillation, the entire product of the reaction can be used if desired but usually it is preferred to purify it.

It is known that hydroxynitroalkanes revert to nitroalkane and aldehyde under alkaline conditions, so in this embodiment, it is possible that the hydroxynitroalkane does decompose under the reaction conditions to yield formaldehyde and nitroalkane; the formaldehyde then reacts with the 2-substituted azoline to yield the ethenyl azoline which, in turn, reacts as previously described with the nitroalkane residue released by the hydroxynitroalkane. The preparation of a compound of this invention by this embodiment is described in Example 1.

The preferred embodiment of this invention is to prepare the ethenyl azoline in situ by condensing a 2-substituted azoline with formaldehyde from a formaldehyde source and reacting the resulting product with a secondary nitroalkane, preferably in the presence of a condensation catalyst. This embodiment is preferred to the two described previously because of the lower costs of the reactants. The reaction releases 1 mole of water and in general is conducted in the same manner as the one just described. The nitroalkane can be introduced to the reaction vessel at the start of the reaction as in Example 2, or it can be added later after the reaction of formaldehyde with the azoline is complete as in Example 14.

Further details on the preparation of the compounds of this invention are given in the examples. Henceforth these nitro-azolines will be referred to as nitro-oxazolines and nitro-imidazolines.

The nitro-oxazolines and nitro-imidazolines of this invention are useful as plasticizers for nitrocellulose and as intermediates for the preparation of amino-oxazolines and amino-imidazolines.

The nitro-oxazolines and nitro-imidazolines of this invention are employed as plasticizers in nitrocellulose lacquers in the same manner as is used for other such plasticizers as is known to those skilled in the art. In general, these nitro-oxazolines and nitro-imidazolines are employed in conventional lacquers in an amount of from about 75% to about 125% by weight of the weight of the nitrocellulose.

Amino-oxazolines and amino-imidazolines can be prepared from the nitro-oxazolines and nitro-imidazolines of this invention by hydrogenation in the presence of a hydrogenation catalyst, e.g. Raney nickel at about 1000 p.s.i.g. at about 30° C. in accordance with procedures known in the art. However, if R_1 , R_2 , or R_3 contain unsaturated linkages, they will probably be hydrogenated in the presence of Raney nickel.

Azolines useful for the preparation of the nitrooxazolines and nitro-imidazolines in the practice of this invention can be obtained commercially or they can be prepared. Commercially available 2-substituted oxazolines and 2-substituted imidazolines having an alkyl, arylalkyl or alkenyl radical in the 2-position are satisfactory for the practice of this invention. Several methods of preparation of 2-substituted oxazolines and 2-substituted imidazolines are known in the art, and any method giving an alkyl, alkenyl, or arylalkyl radical in the 2-position will give oxazolines and imidazolines satisfactory for the practice of this invention. Oxazolines substituted in the 4- and 5-positions and imidazolines substituted in the 1-, 4-, and 5-positions are also satisfactory provided they have an alkyl, alkenyl, or arylalkyl radical on the 2-position. One procedure which has given satisfactory results for preparing such compounds is given by H. L. Wehrmeister, J. Org. Chem. 26, 3821 (1961).

The ethenyl azolines employed in the practice of this invention are readily prepared from 2-alkyl oxazolines, 2-arylalkyl oxazolines, 2-alkenyl oxazolines, 2-alkyl imidazolines, 2-arylalkyl imidazolines, and 2-alkenyl imidazolines by treating them with a formaldehyde source such as formaldehyde or paraformaldehyde as is known by those skilled in the art and as described in Example 14. Also, a satisfactory procedure is given by H. L. Wehrmeister, J. Org. Chem. 27, 4418 (1962).

In general, 2-substituted oxazolines can be readily prepared by reacting an aliphatic or aromatic monocarboxylic acid having 2 or more carbon atoms with an alkanolamine having the following general structure:

where R_2 and R_3 are alkyl radicals of from 1 to 3 carbon atoms or hydroxymethyl. R_2 and R_3 can be the same or they can be different. These alkanolamines include but are not limited to 2-amino-2-methyl-1-propanol; 2-amino-2-methyl-1,3-propanediol; 2-amino-2-ethyl-1,3-propanediol; 2-amino-2-hydroxymethyl-1,3-propanediol. When either R_2 or R_3 , or both, are hydroxymethyl, the resulting hydroxyoxazoline can be esterified with aliphatic or aromatic monocarboxylic acids according to methods known in the art and these oxazoline esters are also useful in the practice of this invention. When the carboxylic acid is saturated, R_1 is alkyl; when the carboxylic acid is unsaturated R_1 is alkenyl; when the carboxylic acid is a member of the phenyl aliphatic acid series, R_1 is arylalkyl or aryl, i.e. if the monocarboxylic acid is phenyl acetic acid, R_1 is aryl.

When the alkanolamine is a triol, both R_2 and R_3 will be hydroxymethyl if 1 mole of a monocarboxylic acid is used to form the oxazoline. These hydroxymethyl groups can then be esterified by an aliphatic, an aromatic or an 5 aryl alkyl monocarboxylic acid to form acyloxymethyl groups. Either the same acid used to form the oxazoline can be employed, or a different one can be used. When it is preferred that the hydroxymethyl group be esterified with the same acid used to form the oxazoline, it is convenient to react the alkanolamine with 3 moles of acid 10 whereupon the di-ester oxazoline is formed in a single step.

Similarly, if the alkanolamine is a diol, and 1 mole of acid is used, either R_2 or R_3 is hydroxymethyl and the 15 other is an alkyl group of from 1 to 3 carbon atoms. The hydroxymethyl group can similarly be esterified, either at the time of oxazoline formation by the use of 2 moles of acid, or in a separate step.

Similarly, 2-alkyl or 2-alkenyl imidazolines can be 20 readily prepared from a monocarboxylic acid having 2 or more carbon atoms by reacting it with a diamine having the following general formula:

where R_2 and R_3 are hydrogen or alkyl radicals of from 1 to 3 carbon atoms. R_2 and R_3 can be the same or they 30 can be different. Y is lower alkyl, aryl, arylalkyl or hydroxyalkyl. These diamines include but are not limited to N^1 -isopropyl-2-methyl-1,2-propanediamine; N^1 -phenyl-2-methyl-1,2-propanediamine; N^1 -(2-hydroxyethyl)-2-methyl-1,2-propanediamine; N -(2-aminoisobutyl)butylamine; and N -(2-aminoisobutyl)benzylamine.

The monocarboxylic acids which can be used to form 35 the oxazolines, imidazolines and their esters can be represented by the formula R_1CH_2COOH where R_1 can be hydrogen, alkyl, arylalkyl, alkenyl or aryl radical of 40 from 1 to about 20 carbon atoms. These acids are the saturated and unsaturated acids of the fatty acid series, including phenyl substituted fatty acids, beginning with acetic acid. There is no known upper limit to the length of the carbon chain which can be employed, but it is practical to utilize the acids having 22 carbon atoms or 45 less because of their relatively low cost. Examples of such acids include but are not limited to acetic, phenylacetic propionic, phenylpropionic caproic, coconut oil fatty acids, tall oil fatty acids, oleic acid, stearic acid, fish oil acids, and the like. Also mixtures of these acids can 50 be employed in preparing these oxazolines and imidazolines.

The nitroalkanes used in the practice of this invention are secondary nitroalkanes having from 3 to 6 carbon atoms in the molecule, including but not limited to 55 2-nitropropane, 2-nitrobutane, nitrocyclohexane, and preferably 2-nitropropane. The monohydroxy nitroalkanes used in the practice of this invention are those having from 4 to 6 carbon atoms in the molecule and having the nitro group and an alkyl group in the 2-position, preferably 2-nitro-2-methyl-1-propanol. The commercial 60 grade materials are fully satisfactory for the practice of this invention.

Acid catalysts suitable for the practice of this invention include inorganic mineral acids such as sulfuric, hydrochloric, and phosphoric acids, organic carboxylic and sulfonic acids such as formic, benzenesulfonic, p-xylene-sulfonic, toluenesulfonic, naphthalenesulfonic acids, inorganic and organic salts such as sodium bisulfate, monoammonium phosphate, calcium chloride, zinc chloride, 70 aluminum chloride, ammonium chloride, ammonium bromide, hydroxyl-ammonium chloride, boron trifluoride, boron trifluoride-ether complex, and halogen, such as iodine. Iodine, p-xylene-sulfonic acid, zinc chloride, and sodium bisulfate have been found to be particularly advantageous catalysts.

The products of this invention and process for the preparation therefor can best be illustrated by the following examples:

Example 1

The preparation of 2-(3-nitro-1,3-dimethylbutyl)-4,4-dimethyl-2-oxazoline was conducted as follows:

Into a 500 ml. round bottomed flask was charged 60 g. (0.5 mole) of 2-nitro-2-methyl-1-propanol, 74.0 g. (0.58 mole) of 2-ethyl-4,4-dimethyl-2-oxazoline, and 1 gram of iodine catalysts. The nitromethylpropanol dissolved readily in the oxazoline with adsorption of heat. Toluene, (100 ml.) was added to assist in removal of water of reaction. The flask was connected to an 18" Vigreux column equipped with a water separator and a reflux condenser and sufficient heat was applied to initiate reflux. Heating at reflux was continued for about 17 hours during which time the temperature gradually rose to about 164° C.

The residue was flash distilled. One fraction was taken at B.P. 39-156° C. at 20 mm., and a second one boiling at 88-172° C. at 1 mm. The residue was discarded, the two fractions combined and redistilled through an 18" Vigreux column. The product recovered was predominantly 2-(3-nitro-1,3-dimethylbutyl)-4,4-dimethyl-2-oxazoline and analyzed as follows:

The quantity of catalyst chosen for this example was greater than that in Example 1 to reduce the reaction period. The 2-nitropropane acted as the water-entraining solvent until it was substantially consumed by reaction. The flask was equipped with a sealed stirrer and thermometer and was attached to an 18" Vigreux column equipped with a water separator and a reflux condenser. The mixture was heated at reflux for about 9 hours during which time the temperature rose to about 152° C.

The pot residue was flash distilled and a cut boiling at 106° C. to 125° C. at 1.5-2.5 mm. was fractionated through an 18" Vigreux column. A relatively pure cut boiling at 90-110° C. at 1.5 mm. was taken as the principal product.

Example 3

Example 2 is repeated except that 2-isopropenyl-4,4-dimethyl-2-oxazoline is used in place of 2-ethyl-4,4-dimethyl-2-oxazoline and the paraformaldehyde is omitted. The expected product, 2-(3-nitro-1,3-dimethylbutyl)-4,4-dimethyl-2-oxazoline, is obtained.

Examples 4-21

Following the procedure of Example 2, compounds corresponding to the general formula are obtained having the substituents as identified in Table 1 in the R₁, R₂, and R₃ positions, when the starting oxazolines are prepared from the acids and alkanolamines listed in Table 1.

TABLE 1

Ex. No.	Ratio Acid/Hydroxy Group	Starting Oxazoline prepared from—		Identity of—		
		Acid	Alkanolamine	R ₁	R ₂	R ₃

Infra-red adsorption spectrum	Consistent with subject structure.
Boiling range at 1 mm., °C.	87-93

The nitro-oxazoline produced in the above reaction is incorporated in a nitrocellulose lacquer as the plasticizer therefore in an amount about equal to the weight of the nitrocellulose. A durable, flexible film is formed when the lacquer is applied to the surface of an object and allowed to dry.

Example 2

2-(3-nitro-1,3-dimethylbutyl)-4,4-dimethyl-2-oxazoline was prepared with 2-nitropropane and paraformaldehyde in place of the 2-nitro-2-methyl-1-propanol used in Example 1. To a 500 ml. flask was charged paraformaldehyde 33 g., 2-ethyl-4,4-dimethyl-2-oxazoline 131.5 g., 2-nitropropane 153.5 g., and iodine catalyst 4 g.

Example 22

2-(3-nitro-3-methylbutyl)-4,4-bis(benzoxyethyl)-2-oxazoline is prepared according to the procedure of Example 2 except that 2-methyl-4,4-bis(benzoxyethyl)-2-oxazoline, 360 g. is used in place of 2-ethyl-4,4-dimethyl-2-oxazoline.

Example 23

The preparation of 2-(3-nitro-3-methylbutyl)-4,4-dimethyl-2-oxazoline was conducted as follows:

Into a 500 ml. flask was charged paraformaldehyde 33 g. and 2,4,4-trimethyl-2-oxazoline 115 g. This mixture was heated with stirring for 2 hours at 80-84° C., and then 150 g. of 2-nitropropane and 5 g. sodium bisulfate were added. This mixture was then heated at reflux temperature for 4 hours during which time the temperature rose to 137° C.

The pot residue was flash distilled through an 18" Vigreux column and a cut boiling at 93-113° C. at 0.8 mm. was taken. This cut was fractionated through an 18" Vigreux column and a cut was taken at 90-94° C. and

0.3 mm. yielding 54 g. of product. Analytical data confirmed the expected structure.

Example 24

The preparation of 2 - (3-nitro-1,3-dimethylbutyl)-1-isopropyl - 4,4 - dimethyl-2-imidazoline was conducted as follows:

To a 500 ml. flask was charged 1-isopropyl-2-ethyl-4,4-dimethyl-2-imidazoline 85 g., paraformaldehyde 16.5 g., 2-nitropropane 45 g., benzene 50 ml., zinc chloride catalyst 2 g. The mixture was heated at reflux with stirring at reflux temperature (132-136° C.) for about 5 hours. The mixture was then flash distilled. The heads and tails were discarded and the remainder was fractionated through an 18" Vigreux column. A relatively pure cut was made at 90-95° C. and at 0.3 mm.

The nitro-imidazoline produced in the above reaction is incorporated in a nitrocellulose lacquer as the plasticizer therefor in an amount about equal to the weight of the nitrocellulose. A durable, flexible film is formed when the lacquer is applied to the surface of an object and allowed to dry.

Example 25

The experiment of Example 24 is repeated except that 2-nitro-2-methyl-1-propanol is used in place of paraformaldehyde and 2-nitropropane. 2-(3-nitro-1,3-dimethylbutyl)-1-isopropyl-4,4-dimethyl-2-imidazoline is obtained.

Example 26

The experiment of Example 24 is repeated except that 1 - isopropyl-2-isopropenyl-4,4-dimethyl-2-imidazoline is employed as the starting azoline in place of 1-isopropyl-2-ethyl-4,4-dimethyl-2-imidazoline and the paraformaldehyde is omitted. 2 - (3 - nitro-1,3-dimethylbutyl)-1-isopropyl-4,4-dimethyl-2-imidazoline is obtained.

Examples 27-39

Following the procedure of Example 24, compounds corresponding to the general formula are obtained having the following substituents in the R₁, R₂ and R₃ and Y positions.

TABLE 2

Example No.	Starting Imidazoline prepared from—		Identity of—			
	Acid	Diamine	R ₁	R ₂	R ₃	Y

36	do	N ¹ -benzyl-2-methyl-1,2-propanediamine	H	CH ₃	CH ₃	C ₆ H ₅ CH ₂
37	do	N ¹ -ethyl-2-methyl-1,2-propanediamine	H	CH ₃	CH ₃	C ₂ H ₅
38	do	N ¹ -hydroxyethyl-2-methyl-1,2-propanediamine	H	CH ₃	CH ₃	C ₂ H ₅ OH
39	Phenylpropionic	N ¹ -isopropyl-2-methyl-1,2-propanediamine	C ₆ H ₅ CH ₂	CH ₃	CH ₃	C ₃ H ₇

What is claimed is:

1. The nitro-azoline compounds represented by the following structural formula:

wherein X is selected from the group consisting of —O— and

wherein Y is selected from the group consisting of hydrogen and lower alkyl, aryl, arylalkyl and hydroxyalkyl

70
75

radicals of from 1 to 7 carbon atoms; R₁ is selected from the group consisting of hydrogen and alkyl, arylalkyl, alkenyl, and aryl radicals having from 1 to 20 carbon atoms; R₂ and R₃ are selected from the group consisting of hydrogen, alkyl radicals having from 1 to 3 carbon atoms, hydroxymethyl radical, and the acyloxymethyl group, said acyl group being an aliphatic, aromatic or aralkyl monocarboxylic acyl group of from 2 to 22 carbon atoms, with the proviso that when X is

10

R₂ and R₃ are selected from hydrogen and alkyl radicals of from 1 to 3 carbon atoms.

2. The nitro-oxazoline compounds represented by the following structural formula:

25 wherein R₁ is selected from the group consisting of hydrogen and alkyl, arylalkyl, alkenyl, and aryl radicals having from 1 to about 20 carbons atoms; and R₂ and R₃ are selected from the group consisting of hydrogen, alkyl radicals having from 1 to 3 carbon atoms, hydroxymethyl radical, and the acyloxymethyl group, said acyl group being an aliphatic, aromatic or aralkyl monocarboxylic acyl group of from 2 to 22 carbon atoms.

30 3. The nitro-oxazoline compounds represented by the following formula:

35 wherein R₂ and R₃ are selected from the group consisting of hydrogen, alkyl radicals having from 1 to 3 carbon atoms, hydroxymethyl radical, and the acyloxymethyl group, said acyl group being an aliphatic, aromatic or aralkyl monocarboxylic acyl group of from 2 to 22 carbon atoms.

40 4. 2-(3-nitro-3-methylbutyl) - 4,4 - dimethyl-2-oxazoline.

5. The nitro-oxazoline compounds represented by the following structural formula:

11

wherein R_1 is an alkyl radical having from 1 to 20 carbon atoms and R_2 and R_3 are selected from the group consisting of hydrogen, alkyl radicals having from 1 to 3 carbon atoms, hydroxymethyl radical, and the acyloxymethyl group, said acyl group being an aliphatic, aromatic or aralkyl monocarboxylic acyl group of from 2 to 22 carbon atoms.

6. The nitro-oxazoline compounds represented by the following structural formula:

wherein R_1 is an aryl alkyl radical corresponding to the formula

where x is an integer of from 1 to 14 and R_2 and R_3 are selected from the group consisting of hydrogen, alkyl radicals having from 1 to 3 carbon atoms, hydroxymethyl radicals and the acyloxymethyl group, said acyl group being an aliphatic, aromatic or aralkyl monocarboxylic acyl group having from 2 to 22 carbon atoms.

7. The nitro-oxazoline compounds represented by the following structural formula:

wherein R_1 is an alkenyl radical having from 2 to 20 carbon atoms and R_2 and R_3 are selected from the group consisting of hydrogen, alkyl radicals having from 1 to 3 carbon atoms, hydroxymethyl radical, and the acyloxymethyl group, said acyl group being an aliphatic, aromatic or aralkyl monocarboxylic acyl group of from 2 to 22 carbon atoms.

8. 2 - (3 - nitro - 1,3 - dimethylbutyl)-4,4-dimethyl-2-oxazoline.

9. The nitro-oxazoline compounds represented by the following structural formula:

wherein R_1 is the phenyl radical and R_2 and R_3 are selected from the group consisting of hydrogen, alkyl radicals having from 1 to 3 carbon atoms, hydroxymethyl radicals, and acyloxymethyl group, said acyl group being an aliphatic, aromatic or aralkyl monocarboxylic acyl group of from 2 to 22 carbon atoms.

12

10. The nitro-imidazoline compounds represented by the following structural formula:

5

10

wherein Y is selected from the group consisting of lower alkyl, aryl, arylalkyl, and hydroxyalkyl radicals of from 1 to 7 carbon atoms; R_1 is selected from the group consisting of hydrogen and alkyl, arylalkyl, alkenyl, and aryl radicals having from 1 to 20 carbon atoms; and R_2 and R_3 are selected from the group consisting of hydrogen and alkyl radicals having from 1 to 3 carbon atoms.

11. The nitro-imidazoline compounds represented by the following structural formula:

25

30 wherein Y is selected from the group consisting of lower alkyl, aryl, arylalkyl and hydroxyalkyl radicals of from 1 to 7 carbon atoms; and R_2 and R_3 are selected from the group consisting of hydrogen and alkyl radicals having from 1 to 3 carbon atoms.

35 12. The nitro-imidazoline compounds represented by the following structural formula:

45

40 wherein Y is selected from the group consisting of alkyl, aryl, arylalkyl, and hydroxyalkyl radicals of from 1 to 7 carbon atoms; R_1 is an alkyl radical having from 1 to 20 carbon atoms; and R_2 and R_3 are selected from the group consisting of hydrogen and alkyl radicals having from 1 to 3 carbon atoms.

45 13. 2 - (3 - nitro-1,3-dimethylbutyl)-1-isopropyl-4,4-dimethyl-2-imidazoline.

14. The nitro-imidazoline compounds represented by the following structural formula:

60

65 wherein R_1 is arylalkyl radical corresponding to the formula

70

70 where x is an integer of from 1 to 14; Y is selected from the group consisting of alkyl, aryl, arylalkyl, and hydroxyalkyl radicals of from 1 to 7 carbon atoms; and R_2 and R_3 are selected from the group consisting of hydrogen and alkyl radicals having from 1 to 3 carbon atoms.

13

15. The nitro-imidazoline compounds represented by the following structural formula:

wherein R_1 is an alkenyl radical having from 2 to 20 carbon atoms; Y is selected from the group consisting of alkyl, aryl, arylalkyl, and hydroxyalkyl radicals of from 1 to 7 carbon atoms; and R_2 and R_3 are selected from the group consisting of hydrogen and alkyl radicals having from 1 to 3 carbon atoms.

16. The nitro-imidazoline compounds represented by the following structural formula:

wherein R_1 is the phenyl radical; Y is selected from the group consisting lower alkyl, aryl, arylalkyl, and hydroxyalkyl radicals; and R_2 and R_3 are selected from the group consisting of hydrogen and alkyl radicals having from 1 to 3 carbon atoms.

17. A process for the production of a nitro azoline comprising the steps of:

(a) preparing a mixture, at a mole ratio of about 1:1, of a secondary nitroalkane with an ethenyl azo line represented by the following formula:

wherein X is selected from the group consisting of $-\text{O}-$ and

wherein Y is selected from the group consisting of alkyl, aryl, arylalkyl, and hydroxyalkyl radicals; R_1 is selected from the group consisting of hydrogen, alkyl, arylalkyl, alkenyl, and aryl radicals having from 1 to about 20 carbon atoms; R_2 and R_3 are selected from the group consisting of hydrogen, alkyl radical having from 1 to 3 carbon atoms, hydroxymethyl radical, and the acyloxymethyl group, with the proviso that when X is

R_2 and R_3 are selected from hydrogen and alkyl radicals of from 1 to 3 carbon atoms,

14

(b) heating said mixture at reflux temperature in the presence of from about 0.5% to about 5% by weight, based on the weight of said ethenyl azoline of an acid condensation catalyst until the temperature has risen to about 150° C., and the said nitroazoline compound has been produced, and

(c) recovering the said nitro azoline.

18. The process of claim 17 wherein the 2-ethenyl azoline is a 2-ethenyl-2-oxazoline.

19. The process of claim 17 wherein the 2-ethenyl azoline is a 2-ethenyl-2-imidazoline.

20. A process for the production of a nitroazoline comprising the steps of

(a) preparing a mixture of a 1-hydroxy-2-alkyl-2-nitroalkane and a 2-substituted-2-azoline at a mole ratio of about 1:1 in the presence of an inert solvent and from about 0.5% to about 5% by weight, based on the weight of said 2-substituted-2-azoline, of an acidic condensation catalyst,

(b) heating said mixture at a temperature of from about 100° C. to about 200° C., simultaneously removing therefrom the water of reaction released by said heating, until the reaction is substantially complete, and

(c) recovering the said nitro azoline from the reaction mixture.

21. The process of claim 20 wherein the 2-substituted-2-azoline is a 2-substituted-2-oxazoline.

22. The process of claim 20 wherein the 2-substituted-2-azoline is a 2-substituted-2-imidazoline.

23. A process for the production of a nitro-azoline comprising the steps of:

(a) preparing a mixture of 2-substituted-2-azoline with a formaldehyde source and a secondary nitroalkane at a mole ratio of about 1:1:1 and about 0.5 to about 5% by weight, based on the weight of said oxazoline, of a condensation catalyst and,

(b) heating said mixture at a temperature of from about 100° C. to about 200° C., simultaneously removing therefrom the water of reaction released by said heating, until the reaction is substantially complete and

(c) recovering the said nitroazoline from the reaction mixture.

CERTIFICATE OF CORRECTION

Patent No. 3,354,171

November 21, 1967

Herbert L. Wehrmeister

It is hereby certified that error appears in the above numbered patent requiring correction and that the said Letters Patent should read as corrected below.

Columns 7 and 8, TABLE 1, fourth column, line 6 thereof, for "1-amino-2-methyl-1,3-propanediol" read -- 2-amino-2-methyl-1,3-propanediol --; column 10, lines 69 to 75, column 11, lines 38 to 44, and column 12, lines 38 to 44, for that portion of each formula reading

read

column 13, lines 19 to 26, for that portion of the formula reading " NC_2 " read -- NO_2 --; line 28, before "lower" insert -- of --.

Signed and sealed this 24th day of December 1968.
